CLAIM

The ornamental design for a loudspeaker enclosure, as shown and described.

DESCRIPTION

FIG. 1 is a front perspective view of our ornamental design for a loudspeaker enclosure;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines in the drawings represent unclaimed environment and form no part of the claimed invention.

1 Claim, 7 Drawing Sheets
